UNITED STATES PATENT OFFICE

EDWARD C. DAVIDSON, OF DETROIT, MICHIGAN

COLLAPSIBLE TUBE

Application filed February 8, 1932. Serial No. 591,680.

This invention relates to collapsible tubes for use in dispensing materials or paste like substances of a more or less plastic or viscid nature, such for example, as medicinal salves 5 prepared in a gelatinous or semi-fluid condition, tooth paste, shaving cream or the like.

An object of the invention is to provide an improved means whereby the user may dispense or discharge the contents of the tube 10 in substantially predetermined amounts.

A further object of the invention is to provide a device which may be utilized in connection with collapsible tubes of standard 15 make without any change in the construction thereof and by virtue of which the dispensing of the tube contents may be controlled in accordance with prescribed amounts.

Other objects of this invention will appear 20 in the following description and appended claims, reference being had to the accompanying drawing forming a part of this specification wherein like reference characters designate corresponding parts in the several views.

Fig. 1 is a longitudinal view of a collapsible 25 tube, partly in section, illustrating one way in which the invention may be carried out.

Fig. 2 is a similar view illustrating the method of dispensing the tube contents.

Fig. 3 is another view of similar nature 30 illustrating the condition of the tube after a dispensing operation.

Fig. 4 is a perspective view of a control member which is disposed within the tube for predetermining the discharge of the tube 35 contents.

Fig. 5 is a section through lines 5—5 of Fig. 4 in the direction of the arrows.

Fig. 6 is a perspective view of another form of control member.

Before explaining in detail the present invention it is to be understood that the invention is not limited in its application to the details of construction and arrangement of parts illustrated in the accompanying drawing, since the invention is capable of other embodiments and of being practiced or carried out in various ways. Also it is to be understood that the phraseology or terminology employed herein is for the purpose of description and not of limitation, and it is not

intended to limit the invention claimed herein beyond the requirements of the prior art.

Referring to the drawing herein, I have illustrated by way of example, a present preferred form of the invention. There is illustrated at 9 a collapsible metal tube of conventional construction having at its forward or discharge end a rigid tapered portion 10 converging into a screw threaded neck 11 adapted to be closed by the usual screw cap 55 12. It will be understood that before filling the tube with paste or other contents D the rear end of the tube is open and the entire tube in this condition is cylindrical from the open end to the reduced discharge end. 60

In the present instance, referring particularly to Figs. 4 and 5, a controlling member is provided for permitting the user when applying pressure with his fingers to the tube to predetermine the amount of the tube contents which may be discharged at one time 65 from the tube. A member 13 is provided for this purpose which in the form shown in Figs. 4 and 5 is in the form of a cylindrical plug 14 of a size and shape to fit within the tube and adapted to be disposed at the discharge end thereof as shown in the drawing.

The rear end of this member 13 provides a partition across the interior of the tube, and this cylindrical portion of the member is flattened or relieved at one side 15 to provide a passage to permit the tube contents to be forced past the obstruction. At the same side the member 13 is relieved to provide a tapered or inclined face 16 which, when the member is 70 positioned as shown in Fig. 1, forms a chamber B adjacent the discharge neck. Thus the larger substantially cylindrical end of the member 13 separates the chamber B from the main chamber A of the tube, these chambers 75 normally communicating through the passage C formed by the relieved portion 15. In the form shown in Figs. 4 and 5 the tapered face 16 is preferably grooved or hollowed out to conform to the thumb of the user and facilitate discharge of the tube contents. This member, however, may be provided with a flat tapered face 17, if desired, as shown in 80 the modified form in Fig. 6.

In operating the device the user may dis- 85

100

charge the contents only from the chamber or compartment B of the tube, thus enabling him to dispense a substantially predetermined amount at each operation. Pressure 5 will first be applied with the thumb on the tube wall opposite the relieved portion 15 so as to press the tube wall in uniform contact with this surface as shown at 18 in Fig. 2. At this time the passage C will be closed so that upon continuing the pressure on the tube 10 wall forwardly along the inclined face 16, or 15 17 as the case may be, the contents of the chamber B will be discharged as shown at 19 in Fig. 2. The limit of inward collapse of the tube wall, as shown at 19, will determine 20 the amount of discharge at each operation, which will always be substantially the same. After this operation the end of the tube, which is closed by the usual tab 9a, is coiled 25 up tightly so as to force additional tube contents into the chamber B and to fully expand the wall of the tube throughout its length.

From the foregoing it will be seen that I have provided a relatively simple and efficient means for dispensing the tube contents 25 in predetermined amounts. The control device 13 may be formed of any suitable material such as wood, metal or a composite non-metallic substance, and may be constructed in 30 different sizes to fit different tubes, and may be designed so as to vary the amount of tube contents dispensed. The construction of this device is such as to permit it to be inserted through the open end of the tube after which 35 the tube may be filled and the end closed in the usual manner. Thus the invention does not require any change or modification in the tube construction.

I claim:

- 40 1. A collapsible tube having a discharge neck, a device disposed within the tube adjacent said neck and providing a partition forming a discharge chamber normally communicating by a passage in the partition with the rear portion of the tube, said device co-operating with the tube wall when pressure is applied in the locality of said chamber to close said passage and permit discharge only of the contents of said chamber.
- 45 2. A collapsible tube having a discharge neck, a member disposed within the tube adjacent said neck, said member having an arcuate wall fitting the tube to form a transverse partition and also having a relieved portion providing a chamber adjacent said neck and a passage past said partition connecting the chamber and the rear portion of the tube, said relieved portion cooperating with the tube wall when pressure is applied 50 opposite said member to close the passage thereby permitting discharge only of the contents of the chamber.
- 55 3. A collapsible tube having a discharge neck, a member disposed within the tube adjacent said neck and having a cylindrical 55

portion fitting the major portion of the interior tube wall to provide a transverse partition, said cylindrical portion being relieved at one side to form a chamber adjacent the tube neck and a relatively shallow passage 70 connecting said chamber with the rear portion of the tube, said relieved portion cooperating with the tube wall when pressure is applied progressively from the end of the relieved portion forwardly to control the 75 discharge of the tube contents from said chamber.

4. A collapsible tube having at one end a discharge neck, a member insertable through the opposite end of the tube and adapted to be positioned adjacent said neck, said member separating the tube interior into two chambers and having a passage connecting the chambers, said member also having a face 80 variably spaced from the tube wall and adapted to cooperate with said wall when pressure is applied thereto for predetermineding the amount of tube contents discharged from one of said chambers through said neck.

5. A collapsible tube having at one end a discharge neck, a member insertable through the opposite end of the tube and adapted to be positioned adjacent said neck, said member separating the tube interior into two chambers and having a passage connecting the chambers, said member also having a face 85 variably spaced from the tube wall and adapted to cooperate with said wall when pressure is applied to the wall opposite said member for discharging the tube contents 90 only from the space between said face and wall.

In testimony whereof I affix my signature.
EDWARD C. DAVIDSON.
